FOUNTAIN APPLICATOR HAVING SLIDING SLEEVE WORK-OPERATED VALVE MEANS

Herman Murray, St. Louis, Mo.

Application November 6, 1947, Serial No. 784,319

1. Claim. (Cl. 15—139)

1 The subject matter of this invention relates to applicators, and an object thereof is the provision of an applicator for applying liquid such, for instance, as liquid shoe polish to shoes, cleaning fluid to fabric, water to postage stamps, etc.

Another object of the invention is to provide a device of the character stated, which shall be particularly adapted to hold a liquid which will not spill, or drip from the container of the device, even if held upside down, which cannot evaporate, which can be quickly manipulated to saturate a sponge with the liquid by depressing the sponge when the device is held sideways, or upside down, and which will permit the sponge to be used for spreading the liquid contained in the sponge to an object without admitting more liquid to the sponge while being used as an applicator.

Another object of the invention resides in a device of the character stated which will be low in cost of manufacture, which can be removably attached to a glass, or other container for the liquid, and which will be highly efficient for the purpose designed.

With the above mentioned objects and other objects in view, the invention consists in the novel construction and combination of parts hereinafter described, illustrated in the accompanying drawing, and set forth in the claims hereto appended, it being understood that mere changes in the form, size, proportion, and minor details of construction within the scope of the claim may be resorted to without departing from the spirit of or without sacrificing any of the advantages of the invention.

For a full understanding of the invention, reference is to be had to the following description and accompanying drawing, in which:

Fig. 1 is a sectional elevation of a fluid control for applicators embodying the features of my invention.

Fig. 2 is a side elevation of the device with the protector cap removed.

Fig. 3 is an inverted sectional view similar to Fig. 1, showing a portion of the fluid container broken away and showing the position of parts when feeding fluid to the fluid absorbent applicator member.

In referring to the drawing, it will be apparent that I make use of a suitable glass, or other container which may be in the form of a bottle 1 of desired capacity for holding a suitable liquid 2.

In carrying out my particular invention which

2 is adapted to be carried at the top of the container 1, I employ a suitable cap 3 which, in one embodiment of the invention, may be detachably secured to the neck 4 of the bottle 1 by means such, for instance, as a screw-threaded cap-skirt connection 5, or equivalent connection.

The cap 3 is provided in its top wall with a suitable opening 3' through which a cylindrical valve body member 6 passes downwardly therethrough to enter the neck 4 of the container 1. The valve body is closed at its inner end except for a central opening 7. The upper normally open outer end portion of the valve body 15 merges with the inner end of a cup-shaped holder designated generally as 8, which is provided with an outwardly diverging wall 9, as illustrated. The holder 8 is adapted to contain a suitable dauber, preferably of synthetic sponge material 10, although not necessarily, as it may be of other suitable liquid-absorbent material such, for instance, as felt, or equivalent material. The sponge material is, preferably, although not necessarily, curved at its outer end portion, while the inner end portion of the sponge is preshaped to fit the cavity of the holder 8. The inner end portion of the sponge material is suitably cemented, as at 11, to the inner wall of the holder 8 to prevent removal of the sponge material from the holder. It will be apparent that approximately half of the sponge material projects beyond the wall edge 12 of the holder which end acts as the liquid applicator, or dauber and is designated 13, for spreading fluid onto a surface such, for instance, as fabric to be cleaned of spots, shoes to be cleaned and shined, applying water to postage stamps, etc.

A suitable valve stem 14 is provided with a suitable cross head portion 15. The cross head 15 is anchored within the sponge material a suitable distance above the edge 12 of the holder 8. The valve stem 14 passes centrally downwardly through the sponge material 10 and through the valve body 6. The lower extremity of the valve stem 14 passes through the central opening 7 in the inner end wall of the valve body 6 and is soldered, or otherwise secured to the inner end wall of a cylindrical slide valve member 16 which has outer telescopic connection with the valve body 6. There is a suitable shoulder 17 secured to the valve stem 14 adjacent the inner end of the sponge material adapted to limit inward movement of the valve stem 14 by contact with an internal seat 18 at the base of the cup shaped holder 8.

A coiled expansion spring 19 encircles the valve stem 14 in the valve body 6 between the shoulder 17 and the inner end wall of the valve body 6.

The coiled spring 19 holds the slide valve member 16 in its normally closed position to close fluid inlets 20 in the wall of the cylindrical valve body 6 to prevent fluid from entering the valve body and finding its way to the applicator material when the device is in an inverted position unless pressure is applied to the dauber 13 to compress the same sufficiently to move the slide valve 16 past the fluid inlets 20.

In ordinary use as a fluid applicator, the dauber is not compressed sufficiently to actuate the slide valve 16 after it has been once compressed sufficiently to admit fluid from the container to saturate the applicator material. To saturate the applicator material with fluid, the device is inverted when the material is compressed sufficiently to actuate the valve stem 14, which in turn moves the slide valve 16 to a position to uncover the fluid inlets 20 and admit fluid to the cylindrical valve body 6 and then to the applicator material.

The cap opening 3' is larger in diameter than the valve body 6 to provide an annular groove 21 between the wall of the opening 3' and the valve body 6 to receive the outer edge portion of the slide valve member 16 and provide thereby a leak proof joint between the cap 3 and valve body 6 adjacent the fluid inlets 20 when the slide valve member 16 is in its closed position.

In order to protect the applicator material when the device is not in use and to prevent rapid evaporation of the fluid contained by the applicator material and thereby eliminate complete dryness of the material, I employ a closure cap 22 which fits over the applicator material and the holder therefor. The cap 22 is detachably connected at its inner end to the cap 3 by suitable means such, for instance, as screw-threads 23, or their equivalent.

It will be apparent from the foregoing description that I provide a fluid control for applicators that is low in cost of manufacture, highly efficient for the purpose intended, and that the applicator can be used with various classes of fluids used for various purposes.

The many advantages of the herein described invention will readily suggest themselves to those skilled in the art to which it appertains.

What I claim is:

In combination with a fluid container having a screw-threaded neck, a container cap having internal screw-threads for screw-threaded connection with the screw-threaded neck and having external screw-threads for screw-threaded connection with a removable cap supported by the first mentioned cap, the container cap having a top wall having a central opening, a cylindrical valve body having a closed inner end provided with a central opening supported by the top wall of the container cap and projecting inwardly through the cap opening, the side wall of the valve body having opposed inlet openings adjacent the outer end thereof, a cup-shaped holder diverging outwardly from the outer end of the cylindrical valve body, a compressible fluid absorbing dauber having its inner end portion seated in the holder and secured thereto, a valve stem having a cross-head at its outer end anchored in the dauber beyond the outer edge of the holder, said valve stem projecting inwardly through the valve body and projecting through the central opening in the inner closed end thereof, a cylindrical slide valve member having a closed inner end secured to the inner end of the valve stem, the aforesaid valve member being telescoped with the valve body normally closing the fluid inlets to the valve body, a shoulder on the valve stem normally spaced from the outer end of the valve body and normally engaging the inner end of the dauber and serving to limit inward movement of the sliding valve member by engaging the outer end of the valve body, a coiled spring encircling the valve stem engaging the shoulder at its outer end and engaging the closed inner end of the valve body at its inner end.

HERMAN MURRAY.
